UNITED STATES PATENT OFFICE.

JOHN BARBERIE, OF BROOKLYN, NEW YORK.

SAFETY APPARATUS FOR LOCOMOTIVES.

SPECIFICATION forming part of Letters Patent No. 752,815, dated February 23, 1904.

Application filed June 17, 1903. Serial No. 161,875. (No model.)

To all whom it may concern:

Be it known that I, JOHN BARBERIE, a citizen of the United States of America, residing at Brooklyn, in the county of Kings and State 5 of New York, have invented certain new and useful Improvements in Safety Apparatus for Locomotives, of which the following is a specification, such as will enable those skilled in the art to which it appertains to make and use 10 the same.

The object of this invention is to provide a safety apparatus for locomotives by means of which the engineer when traveling at high speed may if existing conditions render it desirable pass a danger-signal only with full knowledge of its existence and without the necessary waste of steam attendant upon a restart from a full stop, a further object being to provide an apparatus of this class which 20 in order to run the train at high speed renders it necessary that all parts of the apparatus be in operative position to bring the train automatically to a standstill if for any reason the engineer fails to see the signal.

25 My invention is fully described in the following specification, of which the accompanying drawings form a part, in which the separate parts of my invention are indicated by suitable reference characters in each of the 30 views, and in which—

Figure 1 is a side elevation of a locomotive provided with my invention; Fig. 2, a rear end view thereof and showing the parts of my invention in operative position; Fig. 3, a plan view of the cab apparatus on the line 3 3 of Fig. 2; Fig. 4, a section on the line 4 4 of Fig. 2; Fig. 5, a diagrammatic perspective view of my apparatus removed from the locomotive, but connected with the boiler; and Figs. 6, 7, and 40 8, detail views of parts of the apparatus as indicated by the section-lines 6 6, 7 7, and 8 8 in Fig. 5; Fig. 9, a plan view, partly in section, of a part of my apparatus; and Fig. 10, a perspective view of a frame which I employ, the support thereof not being shown.

In the drawings forming part of this specification I have shown a cab *a* of a locomotive *a*, provided with a boiler *a*³, and beneath the cab *a* is mounted a part of my apparatus, and

within the cab is the other part thereof, which 50 comprises a system of cylinders and pipes in connection with the boiler *a*³ and with the air-brakes of the locomotive or train to which it may be connected.

Mounted in any convenient place within the 55 cab *a* or, as shown in the drawings, upon the rear end of the boiler *a*³ is a steam-cylinder *b*, provided with a piston *b*², the rod *b*³ of which extends to a point near the right-hand side of said cab and is connected at its outer end with 60 a crank-lever *b*⁴, secured to a horizontally-arranged bar *b*⁵, mounted on the side of the cab, and the bar *b*⁵ is provided with a bevel gear-wheel at one end thereof. The cylinder *b* is also provided with an inlet-pipe *b*⁶ and an outlet-pipe *b*⁷ on one side of the piston *b*², said outlet-pipe being of about one-eighth the area 65 of the inlet-pipe *b*⁶ and serves to carry away the condensed steam from that side of the piston, and on the other side of the piston *b*² is 70 a similar inlet-pipe *b*⁸ and an outlet-pipe *b*⁹, said outlet-pipes being in practice carried through the floor of the cab.

The inlet-pipes *b*⁶ and *b*⁸ are each connected with the steam-supply of the boiler *a*³, and the 75 pipe *b*⁶ is provided with a valve *c*, while the pipe *b*⁸ is provided with a valve *c*², and when one of said valves is operated the piston *b*² is driven in one direction, while if the other of said valves is operated the piston is driven in 80 the other direction, as will be readily seen.

The piston-rod *b*³ is provided near the cylinder *b* with a slide-block *c*³, which is mounted in a casing *c*⁴, and in the innermost position of the piston-rod an opening *c*⁵ therein and an 85 opening *c*⁶ in the casing *c*⁴ register with each other; but if the piston-rod *b*³ be moved the openings will no longer register.

Mounted upon the rear end of the boiler *a*³ is the usual throttle *d*, but which is provided 90 with a rod *d*², which enters one side of the casing *c*⁴, and if the piston-rod *b*³ is in its innermost position the rod *d*² is free to pass through the openings *c*⁵ and *c*⁶ and the throttle may be drawn out to its full extent; but 95 if the piston-rod *b*³ is in its outermost position the rod enters a recess *d*³ in the slide-block *c*³ and the throttle can then be but partially

drawn out, and the steam-supply to the engine being thus reduced the locomotive slackens its speed.

On the same horizontal line or plane as the 5 throttle d and to the rear thereof is a cylinder e , provided with a piston e^2 and piston-rod e^3 , to the end of which is secured a plate e^4 , which bears against a toggle-lever e^5 on the throttle d and which is in connection with 10 the usual locking devices of the throttle, and the cylinder e is provided with an inlet-pipe e^6 , the other end of which is connected with the steam-supply of the boiler, and the pipe e^6 has a valve therein, which is preferably at the 15 right side of the cab, and when steam is admitted to the cylinder e the piston-rod e^3 is driven out and releasing the throttle from any position in which it may be placed forces the same shut, and thereby shuts off the steam- 20 supply to the engine of the locomotive. The cylinder e also has a small pipe e^7 connected with it and which passes through the floor of the cab and serves as a drip-pipe for the condensed steam, and a supplemental pipe e^8 opens 25 into the cylinder e at a point adjacent to the outermost position of the piston e^2 , and the pipe e^8 is provided with a valve e^9 at its end, said valve being in connection with the air-brakes of the locomotive, and when this valve 30 is operated the steam forces the same into a position which permits the air from the brakes to escape, and the brakes are thus set and remain so as long as steam enters the cylinder e , as will be readily understood.

35 Beneath the cab of the locomotive, and preferably on the right-hand side thereof, is mounted a frame f , which is held in its normal position by means of brace-rods f^2 , but which is free to swing forwardly in a horizontal 40 plane, and the frame f consists of a top member f^3 , a pivoted bottom member f^4 , and a removable member f^5 , which is preferably composed of glass or other brittle material, and in the normal position of the frame f the de- 45 structible member f^5 is extended slightly beyond the cab of the locomotive and is adapted to be broken by means of a semaphore or other signal placed in position adjacent to the rails upon which the locomotive runs.

50 The inner end of the bottom member f^4 is preferably provided with a roller and is in operative connection with a vertically-movable rod h , which is normally held down by means of a spring h^2 , and this vertical rod h 55 is connected, by means of a crank-lever h^3 , to the valve h^4 of the steam-pipe e^6 , and if the de-structible member f^5 be removed in any manner the spring h^2 of the rod h forces said rod downward and opens the valve h^4 , thereby 60 admitting steam to the cylinder e and the throttle d is shut off and the air-brakes of the train set and said train brought to a standstill, and the engine cannot be again started until another member f^5 is inserted in place 65 of the one destroyed, as will be readily seen.

The frame f is secured to a vertical rod i , which acts as a pivot for said frame, and the upper end of this rod i is provided with a bevel gear-wheel i^2 , which is in operative connection with the bevel gear-wheel i^3 on the 70 end of the bar b^5 , and, as will be seen, if the valve c be opened the steam enters the cylinder b , and if the throttle d is at this time closed the piston-rod b^3 is driven out, thereby turning the bar b^5 , which by means of the 75 bevel gear-wheels i^2 and i^3 turns the vertical rod i , thereby swinging the frame f out of its operative position, and if the valve c^2 be opened and the valve c closed the steam enters the cylinder b on the other side of the piston b^2 80 and the frame f is again swung into its operative position and the throttle may be opened to its full extent; but while the throttle is in the outward position of the piston-rod b^3 , because of the slide c^3 , said throttle could only 85 be opened a short distance, thereby reducing the amount of steam passing to the engine, and this construction permits the engineer to coast past a signal, but at greatly reduced steam-pressure, and before he can resume 90 full steam he must operate the valve c^2 , thereby placing the destructible member in operative position and these operations of the valves c and c^2 remind him that there is danger ahead and any accident to the train is entirely his 95 own fault.

It will thus be seen that if the engineer does not see a signal the train is automatically stopped. If he does see it and passes it, he does so under reduced steam-pressure, and in order 100 to increase the steam-pressure he must again swing the apparatus into operative position. He may use the regular apparatus of the locomotive without interfering with my invention, and if the train is stopped by a signal he must 105 replace the destroyed member f^5 before he can open his throttle or release the air-brakes, and a time-checking device may also be employed in connection with my invention, which will indicate at what time he operated the 110 apparatus to pass a set signal, and in this way the responsibility of a subsequent accident may be placed, as it is obvious that if the signal had not been set the destructible member would not have been swung out of 115 its operative position; but if the signal had been set the engineer would either have been halted automatically through failure to see it or he would have passed it with full knowledge at the indicated time.

The engineer may also run the engine forward or backward in the yard at yard speed past signals or obstructions without destroying the member f^5 by swinging the same out of position, and if said member is destroyed at any 125 time, the train being immediately brought to a standstill, he can easily replace the same, extra ones being carried for such an emergency, and these members f^5 are easily adjustable in the top and bottom members f^3 and f^4 , sockets 130

being provided in these members f^3 and f^4 for this purpose, and the members f^5 may be wrapped with adhesive tape to prevent the flying of particles thereof. It will also be understood that the valve h^4 of the steam-pipe e^6 could be constructed as an auxiliary throttle to the locomotive, in which case the cylinder e could be dispensed with, and my apparatus may also be adapted to electrically-propelled trains or cars, and various other changes in and modifications of the construction herein shown and described may be made without departing from the spirit of my invention or sacrificing its advantages.

Having fully described my invention, what I claim as new, and desire to secure by Letters Patent, is—

1. A safety apparatus for locomotives, comprising a destructible member mounted beneath the cab of said locomotive, in a radially-movable frame consisting of a vertical pivoted rod, a top member secured to said rod and a bottom member loosely connected with said rod, said frame being radially movable in a horizontal plane and said bottom member thereof being radially movable in a vertical plane, said destructible member being in operative connection with the steam-supply and the air-brakes of said locomotive, substantially as shown and described.

2. A safety apparatus for locomotives comprising a frame, radially movable in a horizontal plane and consisting of a vertical rod, a top member secured thereto, a bottom member loosely mounted on said rod and radially movable in a vertical plane, a displaceable member held between said top and bottom members, said displaceable member being in operative connection with the steam-supply and the air-brakes of said locomotive and means for displacing said displaceable member placed adjacent to the rails upon which said locomotive moves, substantially as shown and described.

3. A safety apparatus for locomotives, comprising a frame movable radially in a horizontal plane, a cylinder mounted in the cab of said locomotive, a piston in said cylinder and a piston-rod connected therewith, a pipe connecting the steam-supply with said cylinder on one side of said piston, a pipe connecting said steam-supply with the other side of said piston, a valve in each of said pipes, a bevel gear-wheel on the top of the pivoted member of said frame, a horizontally-arranged rod in said cab, a bevel gear-wheel on said rod and in operative connection with said first-named gear-wheel and a crank-lever connecting said piston-rod with said horizontally-arranged rod, substantially as shown and described.

4. In a safety apparatus of the class described, a cylinder mounted in the cab of a locomotive, a pipe connecting the rear end of said cylinder with the steam-supply of said

locomotive, a valve in said pipe, a supplemental pipe connected with said cylinder and centrally thereof, a valve in the end of said supplemental pipe in operative connection with the air-brakes of said locomotive, a frame mounted beneath the cab of said locomotive, said frame comprising a pivotally-mounted vertical rod, a top member secured to said vertical rod, a bottom member loosely mounted on said vertical rod, a destructible member held between said top and bottom members, a spring-operated rod in connection with said valve and also in operative connection with the inner end of said bottom member, said bottom member being radially movable in a vertical plane and means for destroying said destructive member and thereby operating said spring-operated rod and said valve, substantially as shown and described.

5. A safety apparatus for locomotives, comprising a frame mounted beneath the cab of said locomotive, a displaceable member mounted in said frame, said frame consisting of a vertical pivot member, a top member fixed to said vertical member and a bottom member loosely mounted on said vertical member, a cylinder in the cab of said locomotive and provided with a piston and piston-rod connected therewith, said piston-rod being also in operative connection with said vertical pivot member of said frame, steam-supply pipes in connection with said cylinder on each side of said piston, a valve in each of said steam-supply pipes, a supplemental cylinder in said cab, a piston and piston-rod thereon adapted to operate upon the throttle of said locomotive, a steam-supply pipe connected with said supplemental cylinder, a valve in said last-named supply-pipe in operative connection with said loosely-mounted member, a supplemental pipe connecting said supplemental cylinder with the air-brakes of said locomotive and means for displacing said displaceable member, substantially as shown and described.

6. A safety apparatus for locomotives, comprising a frame radially movable in a horizontal plane and consisting of a vertical pivot member, a top member secured thereto, a loosely-mounted bottom member radially movable in a vertical plane, a cylinder in said locomotive and provided with a piston and piston-rod therefor, a throttle, a pin on said throttle, a casing about said piston-rod, an opening through said casing and said piston-rod through which said pin is adapted to pass when said piston-rod is in one position, said pin and throttle being stopped by said piston-rod when in its other position, steam-supply pipes and valves therefor in said cylinder on each side of said piston, said piston-rod being in operative connection with said vertical pivot member of said frame and adapted to swing the same in a horizontal plane, a supplemental cylinder in said locomotive, a steam-supply

- pipe therefor, a valve in said last-named supply-pipe, a vertically-movable spring-operated rod in operative connection with said last-named valve and said bottom member of said frame, a displaceable member in said frame, the removal of which releases said bottom member and operates said spring-operated rod and valve connected therewith, a piston and piston-rod therefor in said supplemental cylinder, said piston-rod being adapted to bear against and close said throttle, a pipe in connection with said supplemental cylinder, a valve therein and in operation with the air-brake pipes of said locomotive, said valve when operated, being adapted to release the air from said pipes and set said brakes and adjustable means, adjacent to the rails upon which said locomotive moves, for displacing said displaceable member, substantially as shown and described.
7. In an apparatus of the class described, a movable frame, a displaceable member held therein and means for operating said frame, substantially as shown and described.
8. In a safety apparatus for locomotives provided with the usual boiler, engine, steam-supply pipes and throttle, a movable frame, a displaceable member in said frame and means for locking said throttle when said frame is in one position and for releasing said throttle when said frame is in its other position, substantially as shown and described.
9. In an apparatus of the class described, a radially-movable frame one of the members of which is radially movable in the plane of said frame, a displaceable member in said frame and serving to hold said radially-movable member in position, substantially as shown and described.
10. In a safety apparatus for locomotives provided with the usual boiler, engine, steam-supply pipes and throttle, a radially-movable frame, one of the members of which is radially movable in the plane of said frame, a displaceable member in said frame and serving to hold said radially-movable member in position, devices connecting said radially-movable member with said steam-supply pipes

and means for displacing said displaceable member, substantially as shown and described. 50

11. In a safety apparatus for locomotives provided with the usual boiler, engine, steam-supply pipes and throttle, a movable frame, a cylinder adjacent to said throttle, a piston and piston-rod in said cylinder, said piston-rod being in operative connection with said frame, devices for locking said piston-rod by means of said throttle when said throttle is open and means for locking said throttle in a closed position when said piston and piston-rod are operated, substantially as shown and described. 55 60

12. In an apparatus of the class described for locomotives provided with the usual boiler, engine, steam-supply pipes and throttle, a cylinder, a piston in said cylinder, a piston-rod connected therewith, a supplemental steam-supply pipe connected with said cylinder on each side of said piston, a casing about said piston-rod, a pin on said throttle and passing 70 into said casing and through said piston-rod when in its normal position, and means for preventing said pin from passing through said piston-rod when in its other position, substantially as shown and described. 75

13. In a safety apparatus for locomotives provided with the usual throttle and steam-supply pipes, a movable frame, a radially-movable member in said frame, a displaceable member in said frame serving to hold said radially-movable member in position, devices connected with said radially-movable member for closing said throttle when said displaceable member is removed and means for locking said throttle when said frame is moved 85 from its normal position, substantially as shown and described.

In testimony that I claim the foregoing as my invention I have signed my name, in presence of the subscribing witnesses, this 16th 90 day of June, 1903.

JOHN BARBERIE.
